UNITED STATES PATENT OFFICE.

JAMES CHANDLER, OF NEW YORK, N. Y., ASSIGNOR OF ONE-HALF TO
CHARLES NELSON, OF SAME PLACE.

DESIGN FOR AN EXTENSION-PENCIL.

SPECIFICATION forming part of Design No. 33,677, dated December 11, 1900.

Application filed October 20, 1900. Serial No. 33,782. Term of patent 3½ years.

To all whom it may concern:

Be it known that I, JAMES CHANDLER, a subject of the Queen of Great Britain, and a resident of New York city, county and State of New York, have invented and produced a new and original Design for an Extension-Pencil, of which the following is a specification.

My design for an extension-pencil is represented in the accompanying drawings, in which a side elevation of an extension-pencil of my design is represented.

My design comprises a case-section *a*, the surface of which is figured with spiral grooves *b*, a knob *f*, centrally located on one end of the case-section, and a ring *i* in connection

with said knob, and said design also comprises a taper spirally-lined body-section of the extension part of the pencil and the conical-shaped tip *j*, said case-section being of larger diameter than the base of the body-section to which it is connected. 20

What I claim is—

The design for an extension-pencil as shown and described.

Signed at New York city this 15th day of 25 October, 1900.

JAMES CHANDLER.
